UNITED STATES PATENT OFFICE.

FANNY CHERRY MORSE, OF NEW YORK, N. Y.

HIP-BRASSIÈRE ATTACHMENT FOR CORSETS.

1,319,604.

Specification of Letters Patent. Patented Oct. 21, 1919.

Application filed April 2, 1919. Serial No. 286,820.

To all whom it may concern:

Be it known that I, FANNY CHERRY MORSE, a citizen of the United States, and a resident of the city of New York, borough 5 of Manhattan, in the county and State of New York, have invented a new and Improved Hip-Brassière Attachment for Corsets, of which the following is a full, clear, and exact description.

10 The invention relates to corsets, and its object is to provide a new and improved hip brassière attachment for corsets arranged to overlie the corset at the back and hips below the waistline with a view to present a 15 smooth foundation for the back of the outer garment to overlie, and thereby assuring a proper hang of the garment and an exceedingly close, glove-like fit of the same to the wearer's body. Another object is to permit 20 the owner of a corset to readily attach the brassière to the corset.

With these and other objects in view, the invention consists of certain novel features of construction, as hereinafter shown and 25 described and then specifically pointed out in the claim.

A practical embodiment of the invention is represented in the accompanying drawings forming a part of this specification, in 30 which similar characters of reference indicate corresponding parts in all the views.

Figure 1 is a rear face view of the hip brassière shown in position on the corset, parts being in extended position;

35 Fig. 2 is a rear view of the corset and hip brassière in position on the wearer; and

Fig. 3 is an enlarged face view of a modified form of the hip brassière more especially designed for use on corsets worn 40 by stout women, part of the brassière being shown broken out.

The corset 10 is made of the usual two parts 11 and 12 fastened together at the back by a lacing 13. The parts 11 and 12 are 45 provided at the front edges with the usual fastening devices 14 and 15 for closing and opening the corset. The brassière 20 is attached to the back and sides of the corset 10 below the waistline thereof with the lower 50 edge of the brassière conforming approximately to the lower edge of the back and sides of the corset 10, as plainly indicated in Figs. 1 and 2. The brassière 20 is preferably formed of an elastic band 21 pro- 55 vided at its ends with attaching members

22 and 23 of inelastic material and of which the part 22 is attached at its ends by stitches 24 to the corset part 11 while the other attaching member 23 is made in two parts 25, 26, of which the part 26 is attached by 60 stitches 27 to the corset part 12. The parts 25 and 26 are adapted to be fastened together by hooks and eyes or other similar fastening means 28 which permit of detaching the part 25 from the part 26 of the end 65 member 23 thus allowing opening and closing of the brassière 20.

In practice the brassière 20 is under tension when the corset is worn. In donning the corset, the brassière 20 is opened, that is, 70 the part 25 is detached from the part 26 to allow of placing the corset in position on the wearer's body and to tighten the same to the desired degree by the use of the lacing 13. The brassière 20 is then closed by 75 connecting the part 25 with the part 26 by the use of the fastening devices 28, and, as previously stated, the elastic band 21 forming the body of the brassière is now 80 under tension. It will be noticed that by 85 the arrangement described, the brassière tends to give the proper shape to the body of the wearer at the back and hips below the waistline and hence when the outer garment is in position on the wearer's body it 85 hangs properly and fits closely to the wearer's body. In order to prevent the brassière 90 from accidental upward movement, the lower edge of the band 21 is provided with depending hose supporting straps 30 having 90 clasps 31 adapted to engage the wearer's hose at the rear thereof. The brassière is reinforced with suitable vertically disposed stays in the manner of corset construction.

For stout women the brassière 20 is preferably provided at the middle of its elastic body 40 with an inelastic portion 41 but otherwise the construction of the brassière is the same as above described relative to the one shown in Figs. 1 and 2.

I do not limit myself to the means of opening and closing the brassière or attaching the same to the corset as the same may be varied without deviating from my invention.

Having thus described my invention, I claim as new and desire to secure by Letters Patent:—

In combination, a corset having a lacing 110 at the back and a flexible hip brassière ex-

teriorly overlying the back and sides of the corset below the waistline thereof, the lower edge of the brassière conforming approximately to the lower edge of the back and 5 sides of the corset, the said brassière comprising an elastic band provided at its ends with attaching members of inelastic material, one of the attaching members having its outer side stitched to the corset at one 10 side thereof, the other attaching member

being made of two parts arranged one along side the other and of which the inner part is secured to the said band, the outer part having its outer edge stitched to the other side of the corset, and fastening devices arranged 15 along the adjacent edges of the said parts to detachably connect the parts with each other and to hold the elastic band under tension when the brassière is in use.

FANNY CHERRY MORSE.
